PREPARATION OF ALPHA, OMEGA-GLYCOL ESTERS

Seaver A. Ballard and Richard R. Whetstone, Orinda, Calif., assignors to Shell Development Company, Emeryville, Calif., a corporation of Delaware

No Drawing. Application October 1, 1953,
Serial No. 383,685

10 Claims. (Cl. 260—491)

This invention relates to a method of preparing diesters of alpha,omega-dihydroxyalkanes containing at least four carbon atoms. More particularly, the present invention relates to a preferred aspect to a method for the preparation of aliphatic carboxylic acid diesters of alpha,omega-dihydroxyalkanes, i. e., of alkylene glycols, containing at least four carbon atoms. In another preferred aspect the invention pertains to a method of preparing aromatic esters of alpha,omega-dihydroxyalkanes containing at least four carbon atoms. In specific aspects the invention pertains to a method for the preparation of aliphatic carboxylic acid esters of hexamethylene glycol and, in a further specific aspect, to a method for the preparation of diesters of dialkyl-substituted 1,5-pentanediols.

Included in the process of the invention as its essential step is a method for the preparation of diesters of alpha,omega-dihydroxyalkenes containing at least four carbon atoms, which unsaturated diesters may, if desired, be separated as useful products of the process, but which more desirably are hydrogenated to form the above esters of the corresponding alpha,omega-dihydroxyalkanes.

Broadly stated, the invention comprises subjecting to pyrolysis a triester of an alpha,beta,omega-trihydroxy-alkane containing at least four carbon atoms, to form as the principal products of the pyrolysis treatment diesters of alpha,omega-dihydroxyalkenes containing the same number of carbon atoms, which diesters may be hydrogenated to form in excellent overall yield diesters of the desired alpha,omega-dihydroxyalkane. The diesters of the alpha,omega-dihydroxyalkanes readily may be converted to the free glycols by methods that either are specifically known or will be apparent to those skilled in the art to which the invention pertains.

It has been proposed to prepare certain esters of unsaturated monohydric alcohols, e. g., of allyl alcohol and of the theoretical vinyl alcohol, by pyrolysis of diesters of alkylene glycols and by pyrolysis of monoesters of alkylene glycols. In both cases esters of dihydric alcohols are employed as the initial reactants, whereas we desire to produce esters of dihydric alcohols. It also is known that glycerides, such as fats, and lower glycerides, such as triacetin, may be pyrolyzed to form acrolein and, in some cases, ketene. Both of these products obviously are distinctly different from the products that are produced in accordance with the present invention.

It unexpectedly has been discovered in accordance with the invention that carboxylic acid triesters of alpha,beta,omega-trihydroxyalkanes containing at least four carbon atoms may be pyrolyzed to form as the principal products of the pyrolysis carboxylic acid diesters of alpha,omega-dihydroxyalkenes, in excellent yields and with a minimum of formation of undesirable by-products. It unexpectedly has been discovered further that the pyrolysis may be effected with a minimum of accompanying formation of esters of beta,omega- and/or alpha,beta-dihydroxyalkenes, or products of their pyrolysis. The practical value of this latter feature of the invention will be readily ap-

2

parent when the possible difficulty of separating into their pure components mixtures of such isomeric esters, or mixtures of the corresponding saturated glycols or diesters thereof, is considered.

5 It is preferred to employ in the process to which the invention relates esters of the hereinbefore and hereinafter disclosed alpha,beta,omega-trihydroxyalkanes with saturated fatty acids, such as the acetates, propionates, butyrate, valerates, caproates, oenanthoates, caprylates, pelargonates, caprates, and homologous esters, the formates being less desirable. There also may be employed in the process an ester of an alpha,beta,omega-trihydroxyalkane with an unsaturated fatty acid containing one, two, or even more non-aromatic carbon-to-carbon multiple bonds, or esters wherein the acyloxy groups are derived from aromatic carboxylic acids, such as benzoic acid, tolueic acid, and n-butylbenzoic and xyllic acids. In accordance with the invention, the most favorable results in the matter of yield of the desired products and in the overall efficacy of the process are obtained when the triester that is employed is one which the acyloxy groups are derived from a saturated aliphatic monocarboxylic acid containing from 2 to about 8 carbon atoms. The process is particularly effective when there are employed the triacetates of the above-defined trihydric alcohols.

In the execution of the process of the invention, the aforesaid triester of an alpha,beta,omega-trihydroxyalkane is heated to a temperature sufficiently elevated to effect the desired pyrolytic decomposition, but not so high that undesired generalized decomposition of the organic materials that are present occurs. Temperatures of at least 300° C. may be employed in accordance with the invention. Temperatures of at least about 350° C. preferably are employed. Considerably higher temperatures may be employed, if desired, up to about 650° C. Within the indicated range of temperatures, the optimum temperature range depends *inter alia* upon the particular triester that is employed in the process and upon the residence time of the triester at the pyrolysis temperature. Lower residence times may be employed at the higher temperatures, and, conversely, longer residence times may be employed at the lower temperatures. When the pyrolysis is carried out with the aid of suitable catalysts, there can be employed temperatures lower than those that are most effectively applied in the non-catalytic pyrolysis, temperatures down to 100° C. being applicable in appropriate cases.

If the process is executed in a batchwise manner, the residence time, as we employ the expression herein, is simply the time in hours that the batch of the triester is subjected to the pyrolysis temperature. When the process of the invention is executed in a continuous manner, as by passing a stream of the triester into and through a reaction zone heated to the desired reaction temperature, the residence time at the pyrolysis temperature is determined by the liquid hourly space velocity, which is the rate at which the triester, measured in the liquid state, is passed into and through the reaction zone. In quantitative terms, the liquid hourly space velocity is equal to the volume of the triester measured in the liquid state, passed through a unit volume of the reaction space per hour. The liquid hourly space velocity that is employed in the execution of the process of the invention may be varied within relatively wide limits, provided that under the existing conditions of temperature, presence or absence of catalysts, etc., it is such that practicable conversions of the triester to the desired products are obtained, without excessive generalized thermal decomposition of the organic materials that are present. Generally speaking, liquid hourly space velocities within the range of from about 1 hr.⁻¹ to about 50 hr.⁻¹ will be found to be suitable. The optimum value, or range of values, of the liquid hourly

space velocity in any given case depends upon the other conditions under which the process is executed. For example, at temperatures of from about 400° C. to about 550° C. liquid hourly space velocities of from about .5 hr.⁻¹ to about 5 hr.⁻¹ frequently may be employed with particular advantage. At other temperatures, somewhat different liquid hourly space velocities may be particularly advantageous.

Although the residence time (or the liquid hourly space velocity in the case of continuous operations), in conjunction with the pyrolysis temperature, may be employed as an expression of the severity of the pyrolytic treatment, it is particularly convenient to define and to measure the several conditions of the pyrolysis in terms of the proportion of the initial amount of the triester that is converted to other products. We have found that particularly favorable results may be obtained in the practice of the process of the invention when the selected conditions are such that relatively high conversions of the initial triester to other products are obtained. For example, highly favorable results are obtained in the practice of the invention when the conditions of temperature, residence time, and the like, are such that from about 55% to about 85% of the triester is converted to other products, the balance being unchanged. Conditions which lead to lower total conversions, say down to about 10% of the triester, may be employed, although in such cases the amount of the desired products that may be obtained from a given amount of the triester per pass is correspondingly less.

The process of the present invention may be executed in either a continuous, an intermittent, or a batchwise manner, continuous operations being most efficacious. One particularly effective manner of operation comprises passing a stream of the liquid triester of the alpha,beta,omega-trihydroxyalkene through a zone, as an elongated reaction zone, that is heated to the pyrolysis temperature, at a rate that is correlated with the temperature to provide the desired percentage conversion of the triester to other products. The reaction zone preferably is defined by an elongated reaction tube which may be heated either internally or externally by suitable heating means. The pyrolysis tube should be constructed of a suitable thermally and chemically resistant material, such as glass, nickel, stainless steel, Monel metal, or other resistant metals or alloys of metals, quartz, porcelain, or the like. The pyrolysis tube may be otherwise empty, or the tube may be packed with inert or catalytically active solids which favor the desired pyrolytic decompositions. Inert solids serve primarily to assist transfer of heat to the triester and maintenance of the temperature at the desired value, and their presence thereby may desirably increase the overall effectiveness of the process. Inert solids which may be present in the reaction tube include, for example, glass, silica, iron, stainless steel, silicon carbide, carbon, aluminum oxide, ceramic materials, e. g., porcelain, and the like. The inert solids may be employed in the form of pellets, particles, fragments, extruded shapes, rings, and the like. Substances which serve as catalysts for the desired reaction also may be present in the pyrolysis zone, including, for example, activated alumina, calcium phosphate, activated carbon, iodine, p-toluenesulfonic acid, solid acid-reacting salts such as acidic calcium and/or silicon phosphates, and the like. Because of the unexpectedly high yields of the desired products that have been obtained in the herein-described non-catalytic pyrolysis of the stated triesters, and because of the possibility that the presence of catalytically active materials may reduce the advantageously high yields by promoting other, undesired reactions, it is preferred to execute the process in the absence of added catalysts. Inert substances, such as the inert solids referred to above, are not regarded as catalysts.

The process of the invention may be executed with the carboxylic acid ester of the alpha,beta,omega-trihydroxy-alkane in either the liquid phase or in the vapor phase. When the operations are carried out with the triester in

the vapor state, e. g., in a continuous process, it may be desirable to provide a preheater or suitable vaporizer to convert the liquid triester to the vapor state. The vaporous ester may be diluted with an inert diluent gas, such as nitrogen, methane, or the like. Alternatively, the triester in the liquid state frequently may be fed directly into the heated reaction zone and its volatilization and pyrolysis effected simultaneously. If the reaction zone is defined as by an elongated heated reaction tube through which the triester is passed, the initial portion of the tube may serve as a preheater, or vaporizer, the vaporous triester being subjected to further pyrolysis in the remaining portion of the reaction tube. The pressure most conveniently may be maintained at or about atmospheric pressure. However, the invention is not limited to the use of atmospheric pressure, and pressures either above or below atmospheric pressures may be employed if desirable.

The pyrolysis of carboxylic acid triesters of alpha,beta,omega-trihydroxyalkanes containing at least four carbon atoms in accordance with the process of the invention has been found to form products comprising principally diesters of unsaturated diols, which diols contain the same number of carbon atoms as the trihydroxyalkane from which the initial triesters were derived, accompanied by only minor amounts of products of other possible reactions. In fact, the only other products of pyrolysis which have been detected have been relatively small amounts of esters of diolefinic monohydric alcohols which easily may be separated, as by fractional distillation, from the aforesaid esters of unsaturated diols. These esters of diolefinic monohydric alcohols may be recovered as useful products, or they may be hydrogenated to the corresponding saturated monoesters, which also are useful compounds.

The mixture leaving the pyrolysis zone comprises an amount of the carboxylic acid from which the acyl groups of the triester subjected to pyrolysis were derived and one or more diesters of unsaturated diols as the principal products of the pyrolysis. The carboxylic acid, which preferably is a lower saturated aliphatic monocarboxylic acid, may be removed or recovered from the mixture of products in any suitable manner. The entire mixture thus may be cooled to about ordinary room temperatures as by passing it through a suitable heat exchanger in heat exchange with water, air, or other coolant, and the carboxylic acid thereafter removed as by distillation. Another convenient method of removing the carboxylic acid by-product is to subject the mixture as it leaves the pyrolysis zone to a stripping treatment at a temperature sufficiently elevated to volatilize the carboxylic acid but not the esters that are present. Of course, other methods of removing the carboxylic acid by-product may be employed, if desired, as by extraction with a selective solvent (e. g., water, if the carboxylic acid is water soluble) and the like.

If the carboxylic acid diesters of the unsaturated diols are desired as the ultimate products, they may be recovered from the products of pyrolysis and purified as by fractional distillation of the ester-containing portion of the reaction products, any unconverted triester of the alpha,beta,omega-trihydroxyalkane also being separated at this time if desired. The unconverted triester may be recycled through the pyrolysis step of the processes with fresh feed in order to increase the overall conversion of triester.

When the process of the invention is directed in its preferred embodiment to the preparation of esters of alpha,omega-dihydroxyalkanes, i. e., of alkylene glycols, containing at least four carbon atoms, the diesters of unsaturated diols which are formed by the pyrolysis are hydrogenated by treatment with molecular hydrogen in the presence of a hydrogenation catalyst to saturate the olefinic bonds that are present in the molecule. The entire mixture that is produced in the pyrolysis step of the process may be subjected to the hydrogenation treatment, although preferably the carboxylic acid by-product of

the pyrolysis and any of the triester of the alpha-beta-omega-trihydroxyalkane that may be present first are removed. It is preferred to isolate, as by fractional distillation, a fraction comprising essentially the diesters of unsaturated diols, and to subject only this fraction to the hydrogenation treatment. Such a fraction ordinarily is a complex mixture, presumably of isomeric alpha,omega-diacyloxyalkenes which generally are quite difficult to separate one from another. We have found that it is not necessary to separate the mixture of diesters into its individual components, and that, in fact, efficiency in operation is favored by fractionating the pyrolysis products only to such an extent that substantial separation of the above stated fraction is achieved. The fraction may contain varying amounts of possible side-products of the pyrolysis, depending upon the efficiency of the fractionation, the presence of such side-products during the hydrogenation treatment not being detrimental.

The hydrogenation of the fraction comprising essentially the carboxylic acid diesters of the unsaturated diols may be effected by subjecting the fraction to the action of molecular hydrogen in the presence of a hydrogenation catalyst under conditions which favor the reduction of olefinic bonds to saturated carbon-to-carbon bonds. As the hydrogenation catalyst there may be employed any of the metals, or compounds of metals, or mixtures thereof, customarily referred to in the art and employed as hydrogenation catalysts. Suitable metals which may be employed as the hydrogenation catalyst include, for example, Ni, V, Pd, Pt, Cu, Cr, Fe, Co, Ru, Mo, W, Ir, Ru, Ag, and suitable compounds thereof, such as oxides and sulfides thereof. It is preferred to employ the base metal hydrogenation catalysts because they have been found to have a desirably high degree of efficacy and because they are easily and economically prepared. Nickel catalysts, such as the well-known catalyst referred to in the art as Raney nickel catalysts, are particularly desirable. In place of the Raney nickel catalyst, there may be employed nickel catalysts that have been prepared, for example, by thermal decomposition of suitable compounds of nickel, by mechanical subdivision of massive nickel, by electrodeposition, or according to other known methods. Catalytically active compounds of metals which may be employed as the hydrogenation catalyst include, among others, copper chromite, copper oxide, molybdenum oxide, mixtures of oxides of copper and of molybdenum, tungsten sulfide, and tungsten-nickel sulfide. The catalyst may be employed in the finely divided state and suspended in the fraction to be hydrogenated, or it may be carried on an inert or catalytically active supporting material, such as carbon, pumice, silica, clay, alumina, kieselguhr, or the like.

In the hydrogenation step of the process of the invention, the carboxylic acid esters of the unsaturated diols are subjected to the action of the molecular hydrogen at an elevated temperature and under superatmospheric pressures of hydrogen in the presence of the hydrogenation catalyst. Amounts of the catalyst from about 1% to about 20% by weight of the fraction that is to be hydrogenated are generally satisfactory, although either larger or smaller amounts of the catalyst may be employed if desirable, without exceeding the limits of the invention. The temperature and the hydrogen pressure should be sufficiently elevated to cause the desired reaction to take place, but the conditions should not be so extreme that undesired decomposition or other reactions occur. Temperatures of from about 40° C. up to about 300° C. may be employed during the hydrogenation treatment, a preferred range being from about 50° C. to about 150° C. Hydrogen pressures of from about 250 pounds per square inch upwards are suitable. There is no known upper limit to the pressures of hydrogen that may be employed, although for practical reasons it rarely is desirable or necessary to employ hydrogen pressures above about 10,000 pounds per square inch.

A preferred range of hydrogen pressures is from about 500 pounds per square inch to about 5000 pounds per square inch.

The carboxylic acid diesters of unsaturated diols that are produced by the pyrolysis step of the process, or a fraction of the pyrolysis products comprising the same, may be hydrogenated by exposing them to the action of hydrogen gas under the aforesaid conditions of temperature and pressure of hydrogen gas in the presence of the hydrogenation catalyst until absorption of hydrogen is essentially complete. It has been discovered that the theoretically calculated amounts of hydrogen based on the degree of unsaturation of the fraction that is to be hydrogenated, may be absorbed. The absorption of hydrogen may be determined by measuring in any suitable known manner the amount of hydrogen that is absorbed. Alternatively, the hydrogenation may be continued until absorption of hydrogen ceases. The hydrogenation treatment of the invention may be carried out in either a continuous, an intermittent, or a batchwise manner. Any suitable apparatus of the character customarily employed for hydrogenation reactions may be employed.

The hydrogenation step of the process of the invention may be effected in the presence or absence of a suitable solvent, such as an inert organic solvent. Suitable organic solvents include, for example, saturated hydrocarbon solvents, ethers, esters, alcohols, aromatic hydrocarbon solvents, halogen-containing hydrocarbon solvents, and the like. When a solvent is employed it may be used in an amount ranging up to 90% by weight or more of the reaction mixture. The carboxylic acid diesters of unsaturated glycals that are produced by the pyrolysis step of the process thus can be effectively hydrogenated in the form of a 10% to 40% by weight solution in a saturated hydrocarbon or other suitable solvent. However, the presence of an inert solvent during the hydrogenation treatment is not a prerequisite to its successful practice, and, thereof, the invention also includes such hydrogenation when no solvent is added to the reaction mixture.

After completion of the hydrogenation step of the process, the desired carboxylic acid diester of the alpha, omega-alkanediol may be recovered from the mixture in any suitable manner. The catalyst, if suspended in the mixture, may be removed by filtration, centrifugation, or in equivalent ways. The solvent, if one is present, may be removed by evaporation, distillation, or the like, and the products of the hydrogenation thereafter separated in any effective manner, fractional distillation, as under reduced pressure, being preferred. It was a quite unexpected result of the present process that the principal, and frequently the only diester present in appreciable quantities, is the carboxylic ester of the alpha,omega-dihydroxyalkane containing the same number of carbon atoms in the molecule (exclusive of the acyloxy groups) as the triester that was subjected to the pyrolysis. No significant quantities of the possible isomeric esters of beta,omega- and/or alpha,beta-dihydroxyalkanes have been found. There may be present, in minor amounts that may be influenced by the efficiency of the fractionation of the products of the pyrolysis step of the process, the corresponding carboxylic acid alkyl ester, presumably formed by saturation of the aforementioned esters of diolefinc monohydric alcohols. Since these products ordinarily have substantially different boiling points, they may be easily separated during purification of the hydrogenation products.

The process of the invention is particularly valuable for the preparation of carboxylic acid diesters of 1,6-hexanediol, from carboxylic acid triesters of 1,2,6-hexanetriol, the lower saturated aliphatic monocarboxylic acid esters preferably being employed. When a triester of 1,2,6-hexanetriol, e. g., the triacetate, is subjected to pyrolysis in accordance with the process of the invention, the principal product has been found to be a com-

plex mixture of esters of C_6 mono-olefinic diols with the carboxylic acid, possibly with very minor amounts of esters of C_6 diolefinic monohydric alcohols. There also is formed the carboxylic acid from which the acyl groups of the triester were derived. There also may be present varying amounts of unreacted 1,2,6-hexanetriol triester. In the case of the lower saturated aliphatic mono-carboxylic acid esters of 1,2,6-hexanetriol the pyrolysis may be effected advantageously at from about 350° C. to about 500° C. and at a residence time or liquid hourly space velocity of from about 0.5 to about 2.5 hr.⁻¹.

The mixture produced by the pyrolysis may be separated by fractional distillation so as to recover a fraction having an increased content of the diesters of C_6 mono-olefinic dihydric alcohols, and also if desired to recover any of the unreacted triester of 1,2,6-hexanetriol. This may be accomplished by separating from the crude products a fraction rich in diolefinic monoesters, another rich in monoolefinic diesters, and a third containing principally unreacted triester. The carboxylic acid by-product, if low boiling, may be removed as a forerun in the distillation, or it may be taken off with another of the fractions, e. g., the diolefinic monoesters. The necessary cuts to obtain the desired fractions readily can be ascertained by those skilled in the art on the basis of suitable analyses for ester value, unsaturation, etc. In the case of products of the pyrolysis of 1,2,6-hexanetriol triacetate, a fraction boiling at from about 85° C. to about 110° C. under 3 mm. Hg pressure, or over an equivalent temperature range under other pressures, may be separated as the fraction rich in hexylene diacetates. Of course, the esters of other carboxylic acids may distill over a somewhat different range of temperatures.

The fraction rich in hexylene diesters may be hydrogenated under hydrogenation conditions which have been referred to hereinbefore, to saturate the olefinic bonds. After completion of the hydrogenation, any minor amounts of other products may be separated from the diester of 1,6-hexanediol that is formed as the principal product, as by fractional distillation of the products of hydrogenation. If the free hexamethylene glycol rather than its diester is desired as the ultimate product, the ester may be saponified according to any of the methods that are known in the art to obtain the desired glycol.

When reference is made herein to alpha, beta, omega-trihydroxy-alkanes containing at least four carbon atoms, and to their esters, it is intended to refer to those saturated aliphatic triols which contain two primary alcoholic hydroxyl groups and a third alcoholic hydroxyl group all bonded to separate carbon atoms in a chain of at least four carbon atoms, two of the hydroxyl groups being attached to adjacent carbon atoms. Regarding the vicinal hydroxyl groups as attached to the alpha and the beta carbon atoms, the second terminal hydroxyl group, i. e., the one at the terminal, or the omega, carbon atom, may be separated from the beta carbon atom by two or more carbon atoms. We preferably employ triesters of alpha, beta, omega-trihydroxyalkanes in which the omega carbon atom is separated from the beta carbon atom by not more than about 5 atoms of carbon. The carbon atoms in this linear group of four or more carbon atoms may be unsubstituted, or they may be substituted by one or more alkyl groups. It is preferred to employ esters of alpha, beta, omega-trihydroxyalkanes which contain not over about 16 carbon atoms, exclusive of the carbon atoms in the acyl groups.

Representative alpha, beta, omega-trihydroxyalkanes, carboxylic acid esters of which may be converted by the process of the invention to esters of alpha, omega-trihydroxyalkanes include in addition to 1,2,6-hexanetriol, 1,2,4-butanetriol, 1,2,5-pantanetriol, and carboxylic acid esters of analogous and homologous alpha, beta, omega-trihydroxyalkanes. Generally speaking, the esters of alpha, beta, omega-trihydroxyalkanes which we may em-

ploy in the process of the invention have structures according to the formula

$$RCOO—CH_2—(CH_2)_n—CH—CH_2—OOCR$$

5 in which n represents an integral number, preferably one not greater than 5, and R represents a monovalent hydrocarbon group containing up to 18 carbon atoms, preferably an alkyl group, such as a lower alkyl group. We 10 also may employ esters of alpha,beta,omega-trihydroxy-alkanes corresponding to the above formula when one or more of the hydrogen atoms in the formula have been replaced by an alkyl group, preferably a lower alkyl group, such as corresponding esters of 2,5-dimethyl-1,2,6-15 hexanetriol, 2-methyl-1,2,6-hexanetriol, 2,5-diisobutyl-1,2,6-hexanetriol, 2,4-dimethyl-1,2,5-pantanetriol, and the like, the preferred esters of such alkyl-substituted alpha,beta,omega-trihydroxyalkanes being the esters of such alpha,beta,omega-trihydroxyalkanes having not 20 more than two alkyl substituent groups replacing hydrogen atoms in the foregoing formula. From the triesters of the unsubstituted alpha,beta,omega-trihydroxyalkanes and lower aliphatic monocarboxylic acids containing at least four carbon atoms there are obtained corresponding 25 esters of alpha,omega-dihydroxyalkanes with lower aliphatic monocarboxylic acids containing at least four carbon atoms. These products correspond to the structure

$$RCOO—CH_2—(CH_2)_n—CH_2—CH_2OOCR$$

30 in which n represents an integral number not greater than 5 and RCOO represents the acyloxy group of a lower aliphatic monocarboxylic acid containing at least four carbon atoms. Illustrative of these are 1,6-hexanediol 35 dibutyrate, 1,5-pantanediol dicaprylate, and 1,5-pentanediol dicaproate. From esters of alkyl-substituted alpha,beta,omega-trihydroxyalkanes there are obtained according to the process of the invention esters of branched-chain alpha,omega-glycols having structures corresponding 40 to the formula

$$RCOO—CH_2—(CH_2)_n—CH_2—CH_2OOCR$$

in which n represents an integral number not greater than 5 and RCOO represents the acyloxy group of an acid selected from the group consisting of lower aliphatic 45 monocarboxylic acids and aromatic monocarboxylic acids, wherein a hydrogen atom on a beta carbon atom is replaced by a lower alkyl group and from none to one, inclusive, hydrogen atom on a different non-terminal carbon atom of the linear carbon chain is replaced by a lower alkyl group as the only additional substituent. Thus, from 2,4-dimethyl-1,2,5-pantanetriol tributylate we obtain 2,4-dimethyl-1,5-pantanediol ditoluate, from 2,4-dimethyl-1,2,5-pantanetriol tricaproate we obtain 2,4-dimethyl-1,5-pantanediol dicaproate, and from 2,5-di-55 methyl-1,2,6-hexanetriol tributylate we obtain 2,5-dimethyl-1,6-hexanediol dibutylate. The novel esters are useful interalia as plasticizers for polyvinyl chloride.

The following examples will illustrate some of the possible specific embodiments of the invention. It will be 60 understood that the examples are intended only to be illustrative of the invention that is defined more broadly in the appended claims. In the examples, the parts are by weight.

Example I

A vertically positioned cylindrical reaction tube constructed of nickel and having a diameter of .625 inch and a length of 42 inches, was filled with 8 to 14 mesh silicon carbide chips. The top of the tube was closed from the 65 atmosphere and was provided with an inlet through which liquid feed could be supplied in measured quantities. The lower end of the tube was connected through a short water-jacketed condenser to a suitable receiving flask for effluent from the reaction tube. The reaction tube was 70 surrounded by thermostatically-controlled electrical 75

heaters which were regulated with the aid of a thermocouple placed in the interior of the reaction tube.

The reaction tube and its contents were heated to 450° C. Liquid 1,2,6-hexanetriol triacetate then was fed into the top of the reaction tube onto the heated silicon carbide chips at a liquid hourly space velocity of 1.47 hr.⁻¹, the velocity being calculated on the basis of the free space in the packed tube. The liquid product issued from the bottom of the tube and was collected in the receiving flask.

When 215 parts of 1,2,6-hexanetriol triacetate had been fed to the pyrolysis tube, 200 parts of liquid products had collected in the receiving flask. The liquid crude product thus obtained was fractionally distilled under reduced pressure. A fraction distilling from 56.5° C to 62.2° C. under 100 mm. Hg pressure was collected and found to be composed primarily of acetic acid. After distillation of a second fraction, distilling from 42° C. to 89° C. under 3 mm. Hg pressure, there was collected a fraction distilling from 89° C. under 3 mm. Hg pressure to 115° C. under less than 1 mm. Hg pressure, amounting to 81 parts and consisting predominantly of diacetates of non-vinylic hexenediols. Fifty-one parts of unreacted 1,2,6-hexanetriol triacetate were separated as a fraction distilling at 115° C. to 116° C. under less than 1 mm. Hg pressure. Seven parts of residue remained in the still kettle.

A solution of 22 parts of the fraction consisting predominantly of hexenediol diacetates dissolved in 78 parts of isooctane was placed in a hydrogenation bomb with 2 parts of Raney nickel hydrogenation catalyst. The mixture was subjected at 100° C. to the action of hydrogen gas under a pressure of 1400 pounds per square inch until hydrogen absorption ceased. The catalyst was removed by filtration and the filtrate was distilled. There were recovered 14.9 parts of hexamethylene glycol diacetate distilling at 103.5° C. to 106° C. under 3 mm. Hg pressure.

The hexamethylene glycol diacetate was dissolved in 30 parts of anhydrous methanol containing 0.25 part of sodium, and methyl alcohol-methyl acetate azeotrope was distilled from the mixture until the theoretically calculated amount of methyl acetate was removed. The alkali was removed by passing carbon dioxide into the residual solution and filtering off the precipitate. The filtrate was distilled, with collection of 7 parts of hexamethylene glycol at 110° C. to 122° C. under 4 mm. Hg pressure. The hexamethylene glycol melted at 36° C. to 38° C. both alone and when mixed with a sample of glycol prepared by another method and melting at the same temperature.

Example II

The tripropionate of 1,2,6-hexanetriol is pyrolyzed according to the method of the preceding example. The resulting mixed liquid products are fractionally distilled and a fraction comprising predominantly dipropionates of non-vinylic hexenediols is collected separately. This fraction is dissolved in about twice its weight of isooctane. The resulting solution is hydrogenated over copper chromite by treatment with gaseous hydrogen under a pressure of about 2000 pounds per square inch at a temperature of about 150° C. until absorption of hydrogen ceases. After separation of the catalyst the resulting solution is fractionated by distillation under reduced pressure, the fraction comprising the dipropionate of hexamethylene glycol being collected separately. The dipropionate of hexamethylene glycol distills at about 106° C. under 2 mm. Hg pressure.

Example III

A fraction consisting predominantly of diacetates of non-vinylic hexenediols, prepared as in Example I, is hydrogenated in the form of a 25% by weight solution in isooctane in the presence of copper chromite and under a hydrogen pressure of about 2000 pounds per square inch and at about 150° C. The diacetate of hexamethylene

glycol is recovered from the products of the hydrogenation according to the procedure illustrated in Example I.

Example IV

5 Forty-one parts of 2,5-dimethyl-1,2,6-hexanetriol are acetylated by treatment with acetic anhydride in the presence of acetic acid and after standing over night the mixture is rapidly distilled to recover the acetate ester. The ester thus prepared is pyrolyzed by heating at about 425° C. The resulting mixture comprises a mixture of diacetates of non-vinyl 2,5-dimethyl-1,6-hexenediols boiling at about 90° C. to 120° C. under 3 mm. Hg pressure. The diacetate of 2,5-dimethyl-1,6-hexenediol is obtained by hydrogenation of this mixture over Raney nickel catalyst at about 120° C. under about 1200 pounds per square inch hydrogen pressure and fractionally distilling the products of the hydrogenation.

15 2,5-dimethyl-1,2,6-hexanetriol used in this example can be prepared from 2,5-dimethyl-3,4-dihydro-1,2-pyran-2-carboxaldehyde by hydrogenation at 150° C. to 180° C. in aqueous ethanol or other aqueous solvent in the presence of acid and a hydrogenation catalyst, such as Raney nickel catalyst.

20 This application is a continuation-in-part of copending application Serial No. 207,865, filed January 25, 1951, now abandoned, which in turn was filed as a continuation-in-part of application Serial No. 769,066, filed August 16, 1947, now abandoned.

We claim as our invention:

30 1. A process for the preparation of diacetates of non-vinylic 1,6-hexenediols, which comprises pyrolyzing by heating at a temperature within the range of from about 300° C. to about 650° C. the triacetate of 1,2,6-hexanetriol and recovering from the products of the pyrolysis a diacetate of a non-vinylic 1,6-hexenediol.

35 2. A process for the preparation of lower aliphatic monocarboxylic acid diesters of non-vinylic 1,6-hexenediols, which comprises pyrolyzing by heating within the range of from about 300° C. to about 650° C., a lower fatty acid triester of 1,2,6-hexanetriol and recovering from the products of the pyrolysis a lower fatty acid diester of a non-vinylic 1,6-hexenediol.

40 3. A process for the preparation of lower fatty acid diesters of non-vinylic 1,6-hexenediols, which comprises passing a lower fatty acid triester of 1,2,6-hexanetriol through a pyrolysis zone heated to within the range of from about 400° C. to about 550° C. at a liquid hourly space velocity of from about .5 hr.⁻¹ to about 5 hr.⁻¹, whereby said triester is pyrolyzed to the lower fatty acid and lower fatty acid diesters of non-vinylic 1,6-hexenediols.

45 4. A process for the preparation of diacetates of non-vinylic alpha,omega-alkenediols, which comprises pyrolyzing by heating within the range of from about 300° C. to about 650° C. a triester having the formula

50 in which n represents an integral number not greater than 5.

55 5. A process for the preparation of monocarboxylic acid diesters of non-vinylic alpha,omega-alkenediols, which comprises pyrolyzing by heating within the range of from about 300° C. to about 650° C. a triester having the formula

60 in which each RCOO represents the acyloxy group of a lower fatty acid and n represents an integral number not greater than 5.

65 6. A process for the production of a monocarboxylic acid diester of hexamethylene glycol, which comprises pyrolyzing by heating within the range of from about 300° C. to about 650° C. a lower fatty acid triester of

1,2,6-hexanetriol and hydrogenating the pyrolysis product by action thereon of molecular hydrogen under super-atmospheric pressure and at an elevated temperature in the presence of a hydrogenation catalyst to produce a lower fatty acid diester of hexamethylene glycol.

7. A process for the production of monocarboxylic acid diesters of polymethylene glycols, which comprises pyrolyzing by heating within the range of from about 300° C. to about 650° C. an alkanetriol triester having the formula

in which each RCOO represents the acyloxy group of a lower fatty acid and n represents an integral number not greater than 5 to produce esters of non-vinylic alpha, omega-alkanediols and hydrogenating the pyrolysis product by action thereon of molecular hydrogen under super-atmospheric pressure and at elevated temperatures in the presence of a hydrogenation catalyst to produce a monocarboxylic acid diester of the polymethylene glycol having the same number of carbon atoms as said alkanetriol.

8. A process for the preparation of a monocarboxylic acid diester of a polymethylene glycol, which comprises hydrogenating in the presence of a hydrogenation catalyst at a temperature and under a pressure of hydrogen conducive to hydrogenating reactions a product produced by pyrolyzing at temperatures within the range of from about 300° C. to about 650° C. an alkanetriol triester having the formula

in which each RCOO represents the acyloxy group of a fatty acid and comprising at least one diester of a non-vinylic alpha,omega-alkanediol and a fatty acid.

9. A process for the preparation of a monocarboxylic acid diester of hexamethylene glycol which comprises hydrogenating in the presence of a hydrogenation catalyst at a temperature within the range of from about 40° C. to about 300° C. and under a pressure of hydrogen of

from about 250 pounds per square inch to about 10,000 pounds per square inch a mixture produced by pyrolysis at temperatures within the range of from about 300° C. to about 650° C. of a fatty acid triester of a 1,2,6-hexanetriol and comprising at least one fatty acid diester of a non-vinylic 1,6-hexenediol.

10. A process for the preparation of a monocarboxylic acid diester of a non-vinylic alpha,omega-alkenediol, which comprises pyrolyzing a triester selected from the group consisting of (a) triesters of trihydroxyalkanes having the formula

in which each R represents a hydrocarbon group containing up to 18 carbon atoms and n represents an integral number not greater than 5, and (b) those alkyl-substituted triesters of alpha,beta,omega-trihydroxyalkanes, which alkyl-substituted triesters are represented by the foregoing formula when the hydrogen atom on the beta carbon atom is replaced by a lower alkyl group and from none to one, inclusive, hydrogen atom on a different non-terminal carbon atom of the linear carbon chain of the residue of the unsubstituted alpha-beta-omega-trihydroxyalkane is replaced by a lower alkyl group as the only additional substituent and R and n are defined as hereinbefore.
